UNITED STATES PATENT OFFICE

2,443,786

COLLAPSIBLE SWING

Morris Cooper, Chicago, Ill.

Application January 31, 1946, Serial No. 644,507

3 Claims. (Cl. 155—68)

1

This invention relates to swings which may be made of any desired size, but is particularly adapted to be made of wire and of small size for dolls, or the like.

The principal object of this invention is to provide a swing made entirely of wire which may be adjusted to extended position for use and which may be collapsed so that it will occupy but little space for storage or shipping.

Other objects are to provide a doll swing which will be neat and attractive in appearance, which will be durable in use and which may be made at a comparatively low cost and which will have such further novel features and advantages as will appear more fully hereinafter.

In the accompanying drawings illustrating this invention,

Fig. 1 is a side view showing the swing in operative position;

Fig. 2 is a front view of the same;

Fig. 3 is a side view showing the parts partly collapsed or folded; and

Fig. 4 is a side view showing the parts in final collapsed position.

As shown in these drawings, the swing comprises a supporting frame with the swing proper or movable parts swingingly attached thereto. The main frame comprises a back section 6 formed of a single piece of wire having a bottom horizontal portion 7, sides 8 and horizontal top rod or bar 9. The ends of the wire may be butt-welded or otherwise fastened together. The front section 10 is also preferably formed of a single piece of wire and has a horizontal portion 11 with upwardly extending sides 12 having eyes 13 which engage with the top bar or support 9 to provide a hinge between the frame members. Tie rods or braces 14 are pivotally connected with the bottom section or reach 7 by means of eyes 15 and also have eyes or loops 16 which slidably engage with the side members 12.

The swing proper has a substantially U-shaped frame 17 formed of wire with a horizontal reach 18 and vertical portions 19 which are provided with eyes 20 for engagement with the supporting bar 9.

The side bars 19 are provided with washers or bearings 21 which may be welded thereto and which are engaged by rod 22 forming a part of the seat 23. The seat has a back panel made with an outer portion having a horizontal section 24 and sides 25 which are united by a curved portion 26 as shown in Fig. 2. The back panel also has a plurality of U-shaped wires 27 and 28 having their lower ends welded to the horizontal sec-

2

tion 24. All of the vertically arranged back members are also welded to the cross rod 22 thus making a pivotal connection between the back and the swing sides 19. The seat bottom 29 is formed of a substantially U-shaped wire having a front horizontal cross piece 30 and sides 31. The rear ends of the side wires 31 have hooks 32 that take under or engage with the cross rod 18. The seat bottom is pivotally connected to the horizontal bar or section 24 by means of washers or bearings 33 which are welded to the sides 31 and engage with such bar. The seat is also provided with a plurality of cross rods 34 which are welded to the sides 31 and complete the seat proper.

When the swing is adjusted to normal or operative position, the various parts will be arranged as shown in Figs. 1 and 2 as will be readily understood therefrom. When the swing is to be folded or collapsed, the hooks 32 are disengaged from the horizontal bar or section 24 and swung downwardly and forwardly until the ends of the side rods 31 can be swung up in front of the bar and over the same as indicated in dotted lines in Fig. 1. The bottom and back portions of the seat may then be brought into substantial alignment as shown in Fig. 3 and swung against the horizontal bar 18. The loops 16 are then slid upwardly along the sides 12 and the lower ends of the frames 6 and 10 brought together until all of the parts are folded flat together as shown in Fig. 4.

While I have shown and described a preferred form of my invention as adapted for commercial use, it will be noted that changes may be made in the sizes and styling of the same without departing from the spirit of the invention as set forth in the following claims in which I claim:

1. A device of the character set forth, consisting of a substantially rectangular frame formed of wire, a second frame formed of wire having a horizontal reach and having two side pieces pivotally connected to the top of the first frame, tie rods pivotally connected to the bottom of the first frame and slidably connected with the sides of the second frame, a swing formed of wire having a horizontal portion and sides extending up to the top of the first frame and pivotally connected therewith, a seat back pivotally connected with the sides of the swing at a short distance above the lower end thereof, a seat bottom pivotally connected with the lower portion of the back and having arms extending rearwardly which are provided with hooks for engagement with the lower horizontal portion of the swing, the arrangement being such that when the hooks are

in engagement with such portion, the seat will be in normal operative position and the hooks may then be detached and the parts swung so that the back and seat may extend in the same plane and move into the plane of the sides of the swing.

2. In a collapsible swing, the combination of a main frame having a back section formed of a single piece of wire with parallel bottom and top reaches and having a front section also formed of a single piece of wire with a horizontal bottom reach and upwardly extending sides with eyes engaging with the top reach of the first named section, tie rods pivotally connected with the bottom of one of said sections and having eyes slidably engaging the sides of the other section, a swing having a U-shaped frame with a horizontal bottom reach and sides having eyes engaging with the top of the first section, bearings in the sides of the swing, at a short distance above the lower ends thereof, a seat back formed of wire and having a horizontal rod engaging with said bearings, said back extending a substantial distance below the bearings, a seat bottom pivotally connected with the lower portion of the back and having arms extending rearwardly and provided with hooks for engagement with the bottom reach of the swing for holding the seat in operative position.

3. A collapsible swing consisting of a rear frame

portion formed of wire and a front frame portion also formed of wire hingedly connected to the top of the first frame portion, tie wires hingedly connected with the lower end of one frame portion and slidably connected with the sides of the second frame portion, a swing having a horizontal rod and having sides extending upwardly and pivotally connected to the top of the first frame portion, a cross rod pivotally connected with the sides of the swing and arranged parallel to the bottom thereof, a seat back secured to said rod, a seat bottom pivotally connected with the lower portion of the back and having rearwardly extending arms provided with hooks for engagement with the cross rod of the swing, substantially as described.

MORRIS COOPER.
